ELECTRICAL WALL PLATE

Edward G. Bordner, Los Angeles, Calif., assignor, by
mesne assignments, to Sierra Electric, Inc., Gardena,
Calif., a corporation of Wisconsin

Filed Sept. 5, 1967, Ser. No. 8,497

Term of patent 14 years

(Cl. D26—13)

FIG. 1.

FIG. 2.

FIG. 3.

FIG. 4.

FIG. 5.

FIG. 1 is a front elevation of an electrical wall plate embodying my new design;

FIG. 2 is a side elevation of FIG. 1;

FIG. 3 is a plan view of FIG. 1;

FIG. 4 is an enlarged fragmentary section on line 4—4 of FIG. 1; and

FIG. 5 is an enlarged fragmentary section on line 5—5 of FIG. 1.

The characteristic feature of my new design is the formation of side faces of the plate with curved edges and flat planar surfaces having essentially linear junctures with the flat face of the plate, and formation of the top and bottom side faces of the plate with continuous curvatures from less conspicuous juncture with the flat face of the plate.

I claim:

The ornamental design for an electrical wall plate, substantially as shown and described.
